GARAGE DOOR OPERATOR

Stanley Taylor, 17324 2nd Ave., White Rock,
British Columbia, Canada
Filed May 26, 1964, Ser. No. 370,309
3 Claims. (Cl. 268—37)

This invention relates to an apparatus for automatically operating a vertically swingable door, especially a garage door, between the open and closed positions.

It is appreciated that heretofore mechanisms have been devised operable by either movement of or the weight of a vehicle to open a garage door. However, such mechanisms have relied upon systems of counterbalancing weights or springs in order to make the opening and closing of the door fully automatic. These mechanisms are very costly and are susceptible to derangement and must be very carefully balanced in order to operate properly. The present invention overcomes these difficulties by providing a mechanism in which the counterbalancing weight necessary to close the door from its open position is simply the weight of the door itself and, which by the use of a very simple system of levers, is relatively easy to assemble and adjust.

The present invention consists of an automatically operated vertically swingable door, comprising a base, a pair of end-abutting platform members arranged to protrude on both sides of the door below the bottom edge thereof, said platform members being slidably hinged at the abutting ends thereof and being hingedly secured to the base at the other ends thereof, an arm extending from one of the members inwardly of the door, and a pivotally supported lever hingedly secured to the door at one end and linked to the arm at the other end, whereby when the platform members are depressed by a weight thereon, the door swings upwardly into an open position, said door closing by gravity and raising the platform members when the weight is removed.

In the drawings which illustrate embodiments of the invention,

FIGURE 1 is a side elevation of the door applied to a garage showing the door in open position in dotted lines, and

FIGURE 2 is an isometric view of the door assembly. Referring to the drawings, 10 generally represents a garage showing only a portion of the framing thereof and 12 a garage door of the overhead type being shiftable between its closed position as shown in solid lines in FIGURE 1, and its open position as shown in dotted lines in FIGURE 1.

Extending upwardly and biased outwardly from the upper edge 14 of the door is a pair of U-shaped supports 16 carrying rotors 18 which engage a pair of spaced tracks 20, said tracks being secured at their outer ends 22 to an upper portal member 24 and running inwardly of the garage 10, their inner ends 26 thereof being secured to an inner horizontal garage frame member 27. By referring to FIGURE 1, it will be seen that the tracks 20 extending substantially vertically upward at the outer ends 22 and are curved rearwardly to a substantially horizontal position.

The door opening mechanism which is designated generally by the reference numeral 28 essentially consists of an outer platform 29 hingedly connected to an inner platform 30 for vertical movement and being connected to the garage door 12 by a system of levers, generally designated by the reference numerals 31 and 32, whereby the vertical movement of the platforms 29 and 30 are transmitted to the door.

By referring to FIGURE 1, it will be seen that the outer platform 29 consists of two elongated side members 33

2

and 34 disposed longitudinally on each side of the portal 24, and being hingedly connected at their outer ends 36 and 37 respectively, to the ends 38 and 39 respectively, of the lower longitudinal sills 41 and 42 of the garage 10, said sills extending outwardly of the portal 24. The side members 33 and 34 are transversely joined by a suitably reinforced platform floor 44 which extends from the outer ends 36 and 37 of the said side members inwardly to just inside the portal 24 whereby when the garage door 12 is in its normally closed position, the bottom edge thereof will rest upon the platform floor.

The inner platform 30 is constructed in substantially the same manner as the outer platform 29, having two parallel side members 45 and 46 supporting a suitably reinforced platform floor 48, the inner ends 49 and 50 of said side members 45 and 46 respectively, being pivotally connected to the sills 41 and 42 respectively, for vertical swingable movement. The side members 45 and 46 are pierced near their outer ends 52 and 53 respectively, by a transverse pin 55, the end portions 57 and 58 of which project outwardly from said side members 45 and 46 respectively, through longitudinal slots 60 and 61 formed in side members 33 and 34 respectively, intermediately of the ends of said latter side members. Nuts 62 and 63 are threaded on said end portions 57 and 58 and bearing against the outer sides of side members 33 and 34 serve to secure the pin 55 in place. The slots 60 and 61 are of sufficient width and length that the end portions 57 and 58 of the pin 55 are free to both pivot and slide therein to permit the side members of both the outer platform and inner platform to lie supported on the floor 65 of the garage when the door 12 is in its normal open position, as shown by dotted lines in FIGURE 1, and to permit the platform floor 44 of the outer platform to meet the bottom edge of the door when the door is in its normal closed position as shown by solid lines in FIGURE 1.

A pair of lever arms 69 and 70 are pivoted intermediate their ends upon pintles 72 and 73 respectively, secured to structural members 75 and 76 respectively, of the garage, the pivotal mounting permitting the lever arms to swing in a vertical plane about the pivotal axis between the position shown in dotted lines and solid lines in FIGURE 1. The outer ends 78 and 79 of the lever arms 69 and 70 respectively, are pivotally connected to each side of the door near the bottom edge thereof and the inner ends 80 and 81 are cooperatively linked to the inner ends 82 and 83 respectively, of the side members 33 and 34 by links 85 and 86 respectively. The links may be relatively short lengths of plate steel or flexible cable secured to bolts 88 running transversely through each of the side members and lever arms near their inner ends.

By referring to FIGURE 1, it will be seen that when the door is in its normal open position, the upper edge of the door is supported by the tracks 20 and the lower edge of the door by the outer ends 78 and 79 of the lever arms. As the lever arms slope outwardly from their pivotal axis to their outer ends, the weight of the door will tend to force said outer ends outwardly thereby raising the inner ends 82 and 83 of the side members 33 and 34, and the platform 29 will tend to hinge upwardly at the same time carrying platform 30 hingedly upward until the door reaches its normally closed position. The door and platforms are so relatively proportioned in weight that with no extra weight on either the platforms 29 and 30, the door is continually urged to its normally closed position.

In operation, the weight of the front wheels of an automobile rolling on the platform 29 will by its weight, move the said platform downwardly and at the same time platform 30 being pivotally connected to platform 29 will also move downwardly. The downward movement of platform 29 will cause the inner ends 82 and 83 of side mem-

bers 33 and 34 respectively, to move downwardly thereby depressing the inner ends 80-81 of the lever arms 69 and 70 causing the outer ends 78 and 79 of the lever arms 69 and 70 respectively, to lift the door 12 upwardly to its normally open position, as shown in dotted lines in FIGURE 1. At this latter position of the door, the side members 33 and 34 of the outer platform 29 and side members 45 and 46 of the inner platform rest upon and are supported by the floor 65 of the garage. As the automobile rolls forwardly, the front wheels will roll on to inner platform 30 which will therefore hold outer platform 29 downwardly. Before the front wheels of the automobile have run off platform 30, the rear wheels of the automobile will roll on to outer platform 29, the door, therefore, being held upwardly until the said rear wheels have run off platform 30, at which time the door by its own weight will slide downwardly into its normally closed position. When the automobile is driven outwardly from the garage with the door in its normally closed position, the rear wheels will contact platform 30, moving it downwardly which, at the same time, moves platform 29 downwardly, thereby opening the door. The door will therefore stay open until the front wheels have rolled off said outer platform 29.

The foregoing illustrates a door opening mechanism which is especially suited to garages and the like, but is not necessarily confined thereto. It may be adapted for use on doors or gates wherever automatic opening and closing thereof is desired.

What I claim as my invention is:

1. Automatic operating apparatus for a vertically swingable garage door for a garage having side frame members and sills, comprising a pair of end-abutting platform members arranged to protrude on both sides of the door below the bottom edge thereof, said platform members being

slidably and hingedly interconnected at their abutting ends and being hingedly connected at their other ends to the sills, a pair of elongated arms extending from an outer one of the said platform members inwardly of and beneath the door, a pair of elongated levers at each side of the garage pivotally supported on the side frame members for pivotal movement in a vertical plane about axes intermediate their length, each of said levers being linked at one of its ends to an arm and at the other of its ends hingedly connected to the door at the lower edge of the latter, said levers being adapted to swing the door upwardly to an open position when the platform members are depressed by a weight placed on any one of them, said door closing by gravity and raising the platform members when the weight is removed.

2. Automatic operating apparatus as claimed in claim 1 in which the platform members are arranged for movement between a horizontal position when the door is fully open and an inclined position in which their abutting ends are elevated above their other ends when the door is in a fully closed position.

3. Automatic operating apparatus as claimed in claim 1 including horizontally extending track means at the upper edge of the door for guiding the door to a horizontal position as the latter is opened.
